[57] CLAIM

The ornamental design of a holder for eyeglasses or similar article, as shown and described.

DESCRIPTION

FIG. 1 is a front elevational view of a holder for eyeglasses or similar article;

FIG. 2 is a right side elevational view thereof, the side opposite being a mirror image;

FIG. 3 is a top plan view thereof;

FIG. 4 is a rear elevational view thereof;

FIG. 5 is a bottom plan view thereof;

FIG. 6 is a left side, top and front perspective view; and FIG. 7 is a left side top and front perspective view of a second embodiment and a 180 degree view from FIG. 7 would be a mirror image thereof.

The broken line showing of eyeglasses in FIG. 6 is for illustrative purposes only and forms no part of the claimed design.
